VENT CAP

Saul Epstein, Los Angeles, Calif.

Application March 15, 1956, Serial No. 571,619

3 Claims. (Cl. 98—84)

This invention relates to a vent cap for a gas vent pipe, and particularly to an improved vent cap adapted for attachment to the upper end of a gas flue or vent pipe extending through the roof of a building.

Vent caps of this type are exposed to wind and weather. They are designed to prevent water from getting into the exit end of the vent pipe, and to maintain a desired, uniform degree of draft by protecting the vent pipe from downdrafts as well as excessive updrafts. A properly designed vent cap should result in the establishment of a uniform draft for the vent pipe system under varying outdoor conditions of wind and weather. The draft in the vent pipe system should approximate that of an open ended flue or vent pipe performing on a clear, quiet day.

Furthermore, the vent pipe cap should be designed and constructed for rugged, durable service to withstand storms and high winds over a prolonged period of time, without the necessity of maintenance or repairs. In addition, the vent cap should be designed for low cost, efficient mass production. It should consist of a minimum number of readily manufactured parts capable of being produced by the employment of a minimum number of operations and relatively inexpensive machinery.

Accordingly, it is an important object of my invention to provide a rugged and durable vent cap construction designed to withstand all kinds of wind and weather, without the necessity of maintenance or repairs over prolonged periods of service.

Another object is to provide an improved vent cap designed and constructed to counteract the effects of downdrafts and excessive updrafts and to establish a desired, uniform draft in the vent pipe system approaching that of an open ended flue or vent pipe during a clear, quiet day.

A further object is to provide a vent cap designed for construction from sheet materials and for economic mass production by the employment of a minimum number of parts capable of being produced rapidly and efficiently by a relatively few, convenient operations and by the use of inexpensive machinery.

Additional objects will become apparent from the following description:

In general terms, my invention comprehends a vent cap comprising a vent pipe section or stack collar, a flange mounted adjacent the upper end of the vent pipe section, a shield mounted on the flange and extending upward therefrom, and a cap mounted in the shield adjacent the upper end thereof and over the vent pipe section. The upper end of the vent pipe section or stack collar, preferably is made cylindrical in shape.

The flange in this case is annular in shape and is provided with a generally horizontal continuous portion, sloping slightly in a downwardly, outwardly direction, an inner annular continuous portion extending vertically and preferably upwardly of the horizontal portion, and an outer annular continuous portion extending vertically and preferably downwardly from the horizontal portion. The inner annular continuous portion of the flange is made to

fit snugly around the outside surface of the vent pipe section and is suitably fixed thereto, such as by spot welding.

A generally cylindrical shield of greater diameter than the annular flange is mounted concentrically around the flange to extend vertically upward therefrom. The shield is provided with vertical indented portions preferably extending radially inward of the shield and engaging the outer annular portion of the flange. The shield preferably is firmly fixed to the outer annular portion of the flange at the vertical indented portions of the shield, such as by spot welding.

A generally horizontal, circular cap of a diameter substantially equal to that of the annular flange and preferably having a continuous peripheral portion extending vertically downward of the cap is mounted in the shield adjacent the upper end thereof. The peripheral portion of the cap preferably is made to engage the vertical indented portions of the shield, and is rigidly fixed thereto, such as by spot welding.

A more detailed description of a specific embodiment of my invention is given with reference to the drawing, wherein:

Figure 1 is a side elevational view partially in section showing the relationship of the flange, shield, and cap with respect to the vent pipe section;

Figure 2 is a somewhat enlarged fragmentary view in sectional elevation showing the flange of the vent cap mounted on the upper end of a vent pipe section of larger diameter than that shown in Figure 1;

Figure 3 is a bottom view of the vent cap shown in Figure 1 showing the relationship of the diameters of the vent pipe section, the flange and the cap, and the shield;

Figure 4 is a perspective view showing the flange as an unassembled part;

Figure 5 is a perspective view showing an alternative flange; and

Figure 6 is a similar view showing the alternative flange inverted.

Fig. 7 is a fragmentary sectional view, similar to a portion of Fig. 1, but showing the structure of Figs. 5 and 6 in a finished assembly.

In the specific embodiment of my invention shown in the drawing, a cylindrical vent pipe section or stack collar 10 is made of a strip of sheet material, such as a sheet of galvanized iron, formed into a cylindrical section. Suitable dimples 11 are formed on the side of the pipe 10 to increase the effective diameter of the vent pipe section and for suitably wedging the vent pipe section or stack collar 10 into the open end of a vent pipe protruding from the roof of a building.

The upper end of the vent pipe section 10 fits snugly into an annular flange 11 having an inner annular continuous portion 12 extending vertically upward from a generally or approximately horizontal, continuous portion 13, sloping somewhat downwardly toward the outer periphery thereof for water runoff, as best shown in Figure 1. The upper end of the vent pipe section 10 is fixed to the inner annular portion 12 by any convenient means to form a rugged connection, such as by spot welding.

The annular flange 11 is provided with an outer annular continuous portion 14 extending vertically downwardly of the generally horizontal portion 13, approximately the same distance that the inner annular portion 12 extends upward of the portion 13. This results in the formation of a relatively rugged annular flange 11 fixed to the top of the vent pipe section 10, which is snugly fitted inside the inner annular portion 12 and is firmly fixed thereto.

In cases where the vent pipe section 10 has a larger diameter than the diameter of the inner annular portion 12, and has an outside diameter approximately the same as the inside diameter of the outer annular portion 14, the vent pipe section 10 can be fixed to the inside surface

of the outer annular portion 14, such as by spot welding, as shown in Figure 2. If the vent pipe section 10 has an inside diameter approximately equal to the outside diameter of the section 10, it can be fixed to the outside of the outer annular portion 14. These two alternative arrangements will result in a reduction of the cross-sectional area of the open end of the vent pipe section 10, but permit the use of a smaller vent cap assembly for a vent pipe of a given diameter, than in the first case described with reference to Figure 1.

Instead of using a flange 11, such as shown in Figures 1 to 4, a modified flange 16, such as shown in Figures 5 and 6, may be used. The flange 16 is provided with an inner annular continuous portion 17 similar to the inner annular continuous portion 12 of flange 11, a generally horizontal continuous annular portion 18 sloping slightly in a downwardly, outwardly direction similar to the portion 13 of flange 11, and an outer annular portion 19 extending vertically downwardly, similar to portion 14 of flange 11, described above in connection with Figures 1 to 4.

In addition, flange 16 is provided with several radially outwardly extending portions 21. There may be three, four or any desired number of radially extending portions 21. Four such portions are shown in Figures 5 and 6. The top portions 22 of the radial portion 21 preferably are continuations of the generally horizontal portion 18 of flange 16. The vertical side portions 23 preferably are integral with the outer annular portions 19 and are formed to converge somewhat outwardly. Generally vertical segmental annular sections 24 formed concentrically with the outer annular portions 19, and having equal radii, are formed on the extremities of the radially extending portions 21. The outer annular sections 24 preferably are of the same height as the outer annular portions 19, but may be made of a somewhat greater height if desired.

Firmly mounted on the flange 11 or the flange 16, as the case may be, is a generally cylindrical shield 27 having a somewhat greater inside diameter than the outside diameter of the flange 11 at outer annular portion 14, or flange 16 at outer annular portion 19. The shield 27 is made of a strip of sheet material, such as galvanized iron sheet, formed into a cylindrical section and joined firmly at extremities such as by brazing or spot welding, for example. The shield 27 can be provided with several annular beads (not shown) for the purpose of imparting additional rigidity to the shield.

Several vertical indentations 28, such as 3 or 4, for example, are formed in the shield 27 and are equally spaced around the periphery of the shield. The vertical indentations preferably are made with flat, radially positioned sides 29 and curved bottom portions 31 having radii of curvature substantially equal to the radius of the outer annular portion 14 of flange 11, or the outer extremity sections 24 of flange 16. The sides 29 need not necessarily be flat, but may be curved somewhat as they extend into the cylindrical wall of shield 27.

The shield 27 adjacent its lower edge is firmly fixed to the outer annular portion 14 of flange 11, or the radially projecting extremity sections 24 of flange 16, by any suitable means, such as spot welding the shield at portions 31 to the flange in each case. This results in a firm, rugged mounting of shield 27 on the flange 11 or 16, as the case may be, which in turn is firmly mounted on the vent pipe section 10, as described above. Alternatively, the shield 27 may be mounted at portions 31 to tabs extending from the lower edge of outer annular portion 14 of flange 11.

Flange 16 may be mounted on vent pipe section 10 at its inner annular portion 17 with portion 17 fitting snuggly around the upper end of vent pipe section 10, and extending upwardly therealong, as was described in the case of portion 12 of flange 11. This arrangement is best shown in Figure 7.

A generally horizontally disposed, circular, dished cap 32 preferably is positioned inward of the upper edge of shield 27. The cap 32 preferably contains a substantially horizontal circular portion 33 sloping slightly downwardly and outwardly of its center, a gently downwardly sloping annular portion 34 integral with portion 33 through a similar portion 36, and an outer annular portion 37 extending vertically downwardly and preferably having a diameter substantially equal to that of outer annular portion 14 of flange 11, or in the case of flange 16, substantially equal to that of outer annular sections 24.

The cap 32 is rigidly fixed to shield 27 at outer annular portion 37 and vertical bottom portion 31, of vertically extending indentations 28, by suitable means such as spot welding. The cap 32 is positioned centrally over the open end of vent pipe section 10. In this position it is designed to shed water so that the water will run off the lower edge of outer annular portion 37 and drip outside the bounds of vent pipe section 10, preferably upon the outer portions of annular, generally horizontal, but slightly sloped portion 13, and outer annular portion 14 of flange 11.

The effects of winds and air currents passing laterally of the shield 27 is minimized. Components of these lateral air movements pass both upwardly and downwardly in shield 27, around outer annular portion 14 of flange 11, and outer annular portion 37 of cap 32. These components of air movement are exactly oppositely directed and tend to counteract each other. In this manner, their effect on the movement of gases upward through vent pipe section 10 is minimized.

If the upward and downward components of winds are not exactly counteracted in this manner, or if an updraft or downdraft of air develops in shield 27 between outer annular portion 14 of flange 11 or outer annular portion 37 of cap 32, such unbalanced components of air move vertically upward or downward in shield 27 from one end thereof to the other, without having any appreciable effect on the movement of vent gases from the open end of vent pipe section 10. Thus, the vent cap of my invention tends to produce a condition approaching that existing at the open end of an open ended vent pipe or flue on a clear day when there is no appreciable movement of air. This results in a steady, unvarying and unaffected draft in the vent system up through the open end of vent pipe section 10.

It will be observed that the vent cap of my invention is constructed of strip material formed into a minimum number of parts which can be rapidly and efficiently made by mass production methods involving a minimum number of relatively simple operations and requiring relatively simple inexpensive machinery. Also, the assembly and fixing together of the various parts of the vent cap of my invention require a minimum amount of labor. The assembled vent cap is designed for rugged and durable construction resulting in a vent cap requiring a minimum amount of maintenance or repair over prolonged periods of rough usage. The vent pipe section 10 is securely fixed in flange 11 which is ruggedly constructed. Shield 27 is securely fixed to flange 11, and cap 32, in turn, is securely mounted in shield 27.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent structure.

Having described my invention, what I claim as new and desire to secure by Letters Patent is:

1. A vent cap comprising a vertical cylindrical vent pipe section; a generally annular flange having a generally horizontal continuous portion, an inner annular continuous portion extending vertically upward of the horizontal portion, an outer generally annular continuous

portion extending vertically downward of the horizontal portion, and radially extending portions having mounting surfaces extending vertically at equal radial distances from the generally annular flange; a generally cylindrical shield of greater diameter than the annular flange mounted concentrically around the flange to extend vertically upward therefrom, the shield having vertical indented portions fixedly engaging the mounting surfaces of the radially extending portions of the flange; and a generally horizontal circular cap of a diameter substantially equal to that of the outer annular portion of the flange and having a continuous peripheral portion extending vertically downward and fixedly engaging the vertical indented portions of the shield adjacent the upper end thereof.

2. A vent cap comprising a vertical cylindrical vent pipe section, an annular louver having a generally horizontal main body portion and having circumferentially continuous inner and outer vertical flanges, a disc-shaped generally horizontal cap having a vertical circumferential flange, the inner vertical flange of said louver being of a diameter corresponding to the outer diameter of said vent pipe section, and means securing said louver by means of said inner vertical flange to an end of said vent pipe section, said outer vertical flange on said louver and said flange on said cap being of corresponding diameters, a generally annular vertical shield having a vertical height greater than the vertical distance between said louver and said disc-shaped cap, said shield being radially spaced from the outer flange on said louver and the flange on said cap and concentric with said disc-shaped cap and said louver, said shield being indented radially inwardly at circumferentially spaced points, and means securing said shield to said louver and said disc-shaped cap by means of said outer vertical flange on said louver and

5 said annular flange on said disc-shaped cap respectively, said indentations having detent means inside said shield for releasably indexing and positioning said cap and said louver therein in desired spaced relationship prior to permanent assembly.

10 3. A vent cap comprising a vertical cylindrical vent pipe section, an annular louver having a generally horizontal main body portion and having circumferentially continuous inner and outer vertical flanges, a disc-shaped generally horizontal cap having a vertical circumferential flange, the inner vertical flange of said louver being of a diameter corresponding to the outer diameter of said vent pipe section, and means securing said louver by means of said inner vertical flange to an end of said vent pipe section, said outer vertical flange on said louver and said flange on said cap being of corresponding diameters, a cylindrical vertical shield having a vertical height greater than the vertical distance between said louver and said disc-shaped cap, said shield being radially spaced from the outer flange on said louver and the flange on said cap and concentric with said disc-shaped cap and said louver, said shield being indented radially inwardly at circumferentially spaced points, and means securing said shield to said louver and said disc-shaped cap by means of said outer vertical flange on said louver and said annular flange on said disc-shaped cap respectively, the said indentations having radial side walls so spaced apart that said indentations are of substantially rectangular cross sectional shape.
